John Island of Millbury Massachusetts,
Scalers Patent

The Schedule referred to in the Letter, Patent and making part of the same containing a description in the words of the said John Island himself of his improvement in the construction of Broad power looms for weaving plain and Twilled Cloth.

To all people to whom these presents shall come:

Be it known, that I John Island of Millbury, in the County of Worcester, and Commonwealth of Massachusetts, machinist, have invented a new and useful improvement in the construction of Broad power looms, called the improved shuttle motion loom, for weaving plain and twilled cloths, and that the following is a full and exact description of the construction and operation of said machine, as improved by me, and in the words following to wit: The frame of the machine may be made of any material suitably firm and strong; it should be long enough to receive the desired width of the cloth to be woven, and wide enough to admit the lathe to vibrate and the harness to open the way for the passage of the shuttle.

The ends of my machine are constructed of cast iron, each end consisting of two posts and two girts, one about ten inches above the other.

The lower girts are crooked projecting into the frame of the loom about six inches. The sides of the frame consist of a Broad beam, Dead Beam, Back and Front Posts. There are two cast iron cross bars, placed at equal distances from the centre of the frame and resting on the front and back posts. There is a shaft of iron called the Lathe Shaft, extending the length of the frame; the ends resting in boxes, on the crooked girts, at each end of the frame, and the middle resting on one of the cross bars. On each end of this shaft is a crank and near the middle of it, and firmly attached to it is a large cog wheel. This cog wheel, as you stand in front of the frame, is near the left side of the left cross bar. Between this cog wheel and the left cross bar, and firmly attached to the lathe shaft is, a pinion. This is the small pinion. There is another pinion called the large pinion, which is so constructed as to slip directly on over the small one, and contains the small one within it, and may be put on or taken

off at the pleasure of the operator. They are so fastened together, that when one revolvs, the other revolvs, in the same manner. There is a short shaft bearing the cams, having its, ends, resting in boxes, on the cross bars, and is called the cam shaft. Upon this shaft are cams, which move the treadles and the harness, and vary in number according to the cloth to be wove.

The small pinion containing twelve cog, or leaves, and the large pinion twenty four, on the left end of the cam shaft is, a cog wheel of forty four cog, called the cam wheel, which play, into the leaves, of the large pinion.

There is another shaft, called the driving shaft, extending from the end of the frame on the right to the left cross bar. The end on the right rests in a box placed on the left, just in the right hand end of the frame, and the other rests on a standard erected on and firmly attached to the left cross bar, on the left end of this driving shaft is a pinion, the leaves of which play into the cog, of the cog wheel attached to the lathe shaft. On the other end of this driving shaft is, a fast, and loose pulley, for the purpose by means of a belt or band, of connecting the loom with the moving power. The lathe is, made mostly of wood and of sufficient length to contain the shuttle boxes, at the ends. The lathe is, supported on lathe standards at each end. These standards, are of cast iron, and at the bottom turn on pivot, or hinge, for the purpose of giving the lathe a vibrating motion. The pivots, or hinges, one at each end of the frame, are on spurs, projecting from the back of the front posts, into the frame. Near the top of the standard, is, an arm which is, attached to it, and extending downward to the crank on the lathe shaft. At the foot of the standard is, another arm, extending upward, also to the crank on the lathe shaft. This lower arm is called a vibrating arm.

The top end of this vibrating arm is connected to the lower end of the arm first mentioned by means of a belt. At the top end of this vibrating arm is, a slot or mortise, of a circular form and receives the end of the crank on the lathe shaft. The standards and vibrating arms, are alike at each end of the machine. There is, a spring placed between the lower end of the arm, extending from the top of the lathe standard, and the upper end of the vibrating arm, for the purpose of accommodating a person.

your Beam, with which the loom is, contemplated to be finished. It is not intended however to be used when the loom is worked with a common wire or leather friction, but when it is thus worked, they may be secured up, fast together. On the left hand side of the large cog wheel is inserted a pin called the stud roller, and is confined in a slot, and removable at pleasure. The office of this is to throw the shuttle; Near the cog wheel on the latter shaft, at the left of it is the picker or shuttle treadle. This hangs on a hinge attached to the back side of the frame. Upon this treadle, and directly against the lowest point on the cog wheel is, attached the picker shoe. This shoe presents an inclined plane, and receiving the stud roller of the cog wheel revolves. Near the hinge of the treadle is a wire or spiral spring contained in a tube or barrel, after the manner of the patent balance, attached to the frame at the upper end, and the lower end attached to the treadle, to raise the treadle back to its place, after it has been depressed by the stud roller. Two strong staff pulleys, are placed in the rear part of the machine, at equal distances from the centre of the loom, the one on the left being nearly over the picker treadle, the other about two feet from it at the right. A small friction roller or pulley is placed between these two pulleys, but nearer to the left pulley than the other, being at a distance a little more than the thickness of the end of the picker treadle. One end of the strap is, confined to one of the pulleys on the outward side of it and passes over the friction pulley to where it is confined, as mentioned above to the treadle, and then to the outward side of the pulley where it is also fastened. The strong staffs are firmly attached to the two outside pulleys mentioned before. At the upper ends of these staffs are attached strings or cords connected at the other ends to the pickers that throw the shuttle. Between these staffs are brackets hanging on hinges at the back side of the loom. The brackets are connected to the harness by means of strings, or wires, and the harness is suspended from the harness roller. In the front side of the loom is the cloth beam, accommodated on the left hand end, with a ratchet wheel which is moved forward by a dog and thus the cloth is taken up as fast as it is woven.

Explanation of the Drawings,

Fig. 1. Represents an end view of the loom. A. A the frame.

- a. End view of the Lathes shaft.

Operation of the machine.

The band passing over y. y. Fig. 2 being slipped off upon the fast or confined fully n.n. the driving shaft g. Figs. 1&2. is made to revolve, and with it the pinion i. Figs. 1&2. and the leaves of this pinion playing into the large cog wheel c.c. Figs. 1.2&3. the Lathe shaft a in Figs. 1.2.. & 3. to which the cogwheel c.c. is firmly attached, is also made to revolve when the Lathe shaft a revolves. the large pinion c. Fig. 1. (same as z.z. in Fig. 2 and f in Fig. 3.) which is firmly attached to the Lathe shaft, revolves, and the leaves of this pinion playing into the cogwheel u Figs. 1&3. on the Cam shaft c.c. Fig. 3. The large cog wheel u and the Cam shaft c.c. are also made to revolve. At the Cam shaft c.c. Fig. 3. revolving, the cams p.p. Figs. 1&3. are brought alternately against the treadles b.b. Figs. 1&2. and the treadles are alternately depressed and in this way the harness being attached to the treadles the threads of the warp are crossed. When the Lathe shaft a was turned, the crank or. on each end of it ^{as in Fig. 2} were turned also, and these cranks being connected with the vibratory cams, Fig 1. by means of the

insertion of the ends of the cranks, into the circular slot, 13. Fig 1 represents the circular slot in one of the vibrating cranks, and 2 fig 1. the end of one of the cranks,) the vibrating cranks were depressed, and as the upper ends of the vibrating cranks are united, or connected to the Lathe Standards, k Fig 1. and k k in Fig 2 by means of the arms, as seen at h Fig 1. by means of the balls, as at n Fig 1. the Lathe Standards, k and with it the Lathe j Fig 1. (the Standards, at both ends of the loom being alike, and moved in the same way, and turning on a pivot, as at d. d. Fig 1.) is carried toward the back of the loom. When the Lathe shaft a began to revolve, the large cog wheel c Fig 1. revolved with it, and the stud roller d Fig 1. D. 4. 3 being attached to the cog wheel c. c. was carried against the inclined plane of the Picket shoe d Fig 1. and forced down and this picket shoe being upon the picket board, b a. Figs 1 & 2. The treadle was forced downward, also, and the leather band or strap m. m. l. q. Fig 2. (same as a. a. Fig 1.) the vibrating end of the picket treadle resting on the strap between the pulleys 2 & 4 Fig 2. was carried down at the same time, and as this strap m. confined at each end very to the two swag staff pulleys, 2 & 4 in Fig 2. the two pulleys were both turned toward each other and as the swag ^{staff} ~~staff~~ ^{rod} h. & q. of Fig 2. (same as c. c. Fig 1.) are firmly attached to the swag staff, moved toward each other in the same manner and by means of the strings, u & v Fig 2. attached to the Pickets 2. 2. Fig 2. The pickets were brought toward each other also. And by this motion, the shuttle was thrown from one end of the lathe j Fig 2. to the other. When the large cog wheel had performed one revolution, or when the stud roller had forced down the picket treadle, and passed by it, the treadle was immediately brought back to its place by means of the spiral spring contained in the bar. n. l. f. Fig 1. and this left ^{the} end of the strap on the pulley 2 Fig 2. loose, so that the force with which the shuttle was driven from the right hand end of the lathe j Fig 2. to the other end will

carry the picker into the other end of the lathe to the end of it - which by means of the string in Fig 2, will turn the sway staff in Fig 2, to the left and this will bring the strap tight and prepared to know the shuttle back when the sled roller shall again force down the picker & shuttle.

The harnesses are drawn up and down ^{up & down} Figs 1 & 2, by one side of each being connected with each of the treadles as in Fig 2, at each revolution of the Lathe shaft. The lathe is carried forward and back by means of the cranks inserted into the circular slots, one of which slot is seen at 5. Fig 1, and this motion is such that when the lathe is carried up, it is made to beat up against the cloth rapidly, but when it is carried back it is less rapid, and when entirely back is almost stationary, which gives sufficient time for the shuttle to pass.

The foregoing description is for weaving plain cloth, and in order to adapt the loom to weaving Kersey, it is necessary to remove the large pinion from the small one, leaving the small pinion with two bre cogs in its place. The cam shaft and cog wheel attached to it are then taken out, and another cam shaft with a wheel of forty eight cogs, and four cams are put in their place. Two additional treadles are also required and another harness roller. By a similar change of the cam shaft, the number of cams and treadles may be multiplied at pleasure and consequently any kind of double work may be woven and the shuttle motion remain the same.

Improvement claimed:

In all the power looms now in use, and especially those for weaving plain Broad cloth, or Broad Kersey the method of driving the shuttle is by means of sled rollers, inserted into the cams by which the harness is operated. These sled rollers, as they revolve with the cams operate alternately upon treadles, called heel & toe or picker treadles, producing upon them a vibrating motion which is made by means of a pulley and sway staff

17694

319

to operate the shuttle. The usual number of beats, or jolts, for a Loom weaving cloth from ten to twelve quarters wide is forty per minute, and as the cams in a loom for plain cloth revolve but half the number of times the Lath beats, and but a quarter the number of times for Jersey, the motion given to the Stud Rollers is very slow which requires the inclined plane of the picker-shoe, where the Stud Rollers are received, to be very steep or abrupt, in order to give sufficient force to the shuttle, and the motion thus given to the shuttle is a very hard and unnatural one, producing a trembling and agitation throughout the whole Loom. To obviate this difficulty and construct a Loom in which the shuttle motion shall remain the same not only for plain cloth, but for Jersey or any kind of double work, is the object of this improvement. And what follows as any improvement consists first in placing the Lath shaft in such position in the Loom, as to admit of its operating not only the vibrating cams, but of its driving the shuttle.

2° Arranging the vibrating cams to the pivots on which the Lath standards rest, and hanging them on the same.

3° Motoring the shuttle with but one Stud Roller and one picker-buckle.

In testimony that the foregoing is a true Specification of my said improvement, as by me described, I have hereunto set my hand and seal this twenty fifth day of February in the year of our Lord one thousand Eight hundred and thirty three.
